UNITED STATES PATENT OFFICE.

JOHN W. DORAN, OF WILKES-BARRÉ, PENNSYLVANIA, ASSIGNOR TO THE WILKES BARRE LACE MANUFACTURING COMPANY, OF SAME PLACE.

DESIGN FOR A CURTAIN-BORDER.

SPECIFICATION forming part of Design No. 29,458, dated October 4, 1898.

Application filed January 6, 1898. Serial No. 665,859. Term of patent 14 years.

To all whom it may concern:

Be it known that I, JOHN W. DORAN, a citizen of the United States, residing at Wilkes-Barré, Luzerne county, Pennsylvania, have 5 invented and produced a new and original Design for Curtain-Borders, of which the following is a specification, reference being had to the accompanying drawings, forming part thereof, wherein—

10 Figure 1 is a face view of a portion of a curtain illustrating my design. Fig. 2 is an enlarged detail face view of the same. Fig. 3 is a transverse sectional view of the same.

15 The characteristic features of my design are essentially those represented in the accompanying drawings.

In the drawings, A represents the body of a curtain which has a border B raised upon both faces and extending around the edge 20 thereof. The border B has an imperforate

band a, which extends in an unbroken strip from one face to the other of the curtain, and over this band a the border has floating threads b, extending in a zigzag manner in parallel lines across both faces thereof. The interstices formed between the floating threads expose the imperforate band a and the zigzag threads form a purled outer edge c, and they may form or join a purling at the inner edge of the braid or border, as indicated at d. 25 Extending across the zigzag threads b near the inner and outer edges of the braid are series of link-threads e.

What I claim is—

30 The design for a curtain-border, substantially as herein shown and described.

JOHN W. DORAN.
